PUZZLE TOY

Charles B. Root, Morristown, N.J., assignor to
Educational Design Associates

Filed Aug. 14, 1973, Ser. No. 388,132

Term of patent 14 years

Int. Cl. D21—01

U.S. Cl. D34—15 M

FIG. 1

FIG. 2

FIG. 3

FIG. 4

FIG. 5

FIG. 1 is a perspective view of a puzzle toy with one element in an exploded condition showing my new design;

FIG. 2 is a front perspective view thereof;

FIG. 3 is a right side elevational view thereof;

FIG. 4 is a bottom plan view thereof; and

FIG. 5 is a rear elevational view thereof.

I claim:

The ornamental design for puzzle toy, substantially as shown.
